UNITED STATES PATENT OFFICE.

KARL KISSENDORFER, OF OBERNDORF-ON-THE-NECKAR, GERMANY.

CALIPERS.

Application filed November 20, 1923. Serial No. 675,855.

To all whom it may concern:

Be it known that I, KARL KISSENDORFER, a citizen of the German Republic, residing at Oberndorf-on-the-Neckar, Germany, have 5 invented certain new and useful Improvements in Calipers, of which the following is a specification.

The hitherto known beam calipers with means for micrometrical adjustment are 10 necessarily provided with a second slide which is to be fixed prior to the micrometrical adjustment of the slide of the vernier. In a construction of this kind, however, a serious disadvantage arises from the fact 15 that the slide of the vernier in turn cannot be fixed by means of its fixing screw except after the micrometrical adjustment has been carried out, whereby the set measurement, that is to say, the measuring position of the 20 slide of the vernier, will be changed. The measuring differences thus occurring and consequent incorrect readings are an objectionable particularity of calipers of the stated type.

25 This invention relates to an improved beam caliper of the said type and the object of the invention is to provide means for remedying the defect hereinbefore indicated. With this object in view the improvement 30 consists in locating the micrometer screw within a recess in the slide of the vernier so as to dispense thereby with the provision of the usual second slide, and to enable the micrometrical adjustment of the slide by 35 means of the nut of said screw, while the latter is adapted to be fixed automatically by jamming on the beam independently of the slide of the vernier.

With this and other objects in view the 40 present invention consists in the combination and arrangement of parts, as will be hereinafter more fully described, shown in the accompanying drawings and particularly pointed out in the appended claims.

45 In the drawings Figure 1 is a side view of the caliper to illustrate, by way of example, a preferred embodiment of the invention;

Figure 2 is a longitudinal section of the 50 slide of the vernier, otherwise termed the movable jaw, with the micrometer screw shown in full view, but with the nut detached;

Figure 3 is a cross-section on the line 55 A-B of Figure 1 and

Figure 4 is a sectional view of a preferred

construction of the micrometer nut and adjacent parts.

In the embodiment shown the caliper comprises, as usual, a beam *a*, a double transverse arm or jaw *b* integral with the beam and an adjustable jaw *c*, the so-called slide of the vernier, mating therewith and adapted to slide on the beam *a* under the control of a guiding or braking spring *d* which is of usual construction and arrangement.

As will be seen in Figure 2 the movable jaw *c* is recessed as at *e* and a braking member is housed in the recess *e*, the said member being loosely inserted therein, so as to have a certain freedom of play in the plane of the jaw. The braking member is of angular construction comprising a narrow shank or arm *f* adapted to engage in a longitudinal groove *h* in the beam, when the parts are duly assembled, so that the broader shank or arm *g* thereof will be maintained in a position perpendicular to the jaw *c*. Pivotedly connected to the arm *g* of the two-armed braking member is a micrometer screw *i*, the pivoted head of the screw being shaped to form a jamming member *j*. The body or stem of the screw works in a longitudinal recess in the movable jaw, while the nut *k* on the screw is adapted to engage in a transverse slot or recess in the jaw *c* and is provided with a resilient disk or cap *m* to fit snugly therein so as to prevent the screw from back-lashing.

To this end and in order to ensure a snug fitting of the nut *k* in the transverse slot or recess in the jaw *c*, the nut is provided with a coaxial circular recess for the reception of a coiled spring *s* and of the aforesaid disk or cap *m*. The pressure exerted by the spring *s* on the nut and on the cap *m* answers the requirements both of avoiding back-lash between the nut and the screw *i* and of ensuring a snug engagement of the nut in the transverse recess in the jaw *c*.

The micrometer screw *i* is forced constantly outwards by means of a coiled spring *p* embedded in a bore in the jaw *c*, in order to keep the head *j* of the screw in jamming engagement with the contiguous edge of the beam *a*, so that the shank or arm *f* of the braking member engaging in the longitudinal groove *h* of the beam *a* will likewise be jammed. In this manner the jaw *c* will be automatically set or fixed at any position on the beam with relation

to the rigid jaw *b*. As both the braking arm *f* and the jamming head *j* of the micrometer screw *i* allow the jaw *c* to be adjusted longitudinally to any desired extent, 5 due to the amount of free play afforded by the size of the recess *e*, such movement can be brought about readily by turning the nut *k*, the micrometrical adjustment being effected by means of the vernier. By lifting the 10 nut *k* from its engaging seat in the transverse recess of the jaw *c*, the screw *i*, which acts as a kind of a braking lever, will be turned outwards into a position such as shown in Figure 2, so that the jamming and 15 braking effect of the parts *f* and *j* will be discontinued and the jaw *c* may be readily adjusted along the beam.

In the caliper shown in the drawings an auxiliary bar *r* for measuring depth and 20 the like is provided in the beam so as to be adjustable therein. The groove receiving and guiding the said bar in the beam coincides with the groove *h* guiding the braking arm *f* so that a single groove is utilized 25 for both purposes. A particular advantage of the improved caliper further resides in the fact that the scales may be of any desired length since there is no obstacle, such as the second slide hitherto used, to the 30 utilization of the whole of the length of the beam for scales and reading purposes.

Though only one specific embodiment of the invention has been described in the above specification with great particularity of detail, yet it is not to be understood therefrom that the invention is limited to the particular embodiment disclosed. Various modifications in detail and in the arrangement of the parts as well as changes in the form, 40 proportion and size may be made within the scope of the claims without departing from the spirit or sacrificing any of the advantages of the invention.

What I claim is:

45 1. A beam caliper, comprising a beam; a fixed jaw thereon; a second jaw movable along said beam and having a slot; a pivotally-mounted micrometer screw; an adjusting nut on the screw movable with the same into said slot to couple the screw to the movable jaw; and means to which said screw is pivoted for jamming the latter on the beam independently of the movable jaw.

55 2. A beam caliper, comprising a beam; a fixed jaw thereon; a second jaw movable along said beam and having a slot; a pivotally-mounted micrometer screw; an adjusting nut on the screw movable with the same into said slot to couple the screw to the movable jaw; means to which said screw is pivoted for jamming it on the beam independently of the movable jaw; and resilient means for holding the jamming means in its jammed position.

60 3. A beam caliper, comprising a beam; a

fixed jaw thereon; a second jaw movable along said beam and having a longitudinal recess and a transverse slot intersecting the same; a micrometer screw movable into said recess; an adjusting nut on the screw movable therewith into said slot to couple the screw to the movable jaw; and means to which said screw is pivoted for jamming it on the beam independently of the movable jaw. 75

4. A beam caliper, comprising a beam; a fixed jaw thereon; a second jaw movable along said beam and having a longitudinal recess, and also having a transverse slot and a bore communicating with said recess; a micrometer screw movable into said recess; an adjusting nut on the screw movable therewith into said slot to couple the screw to the movable jaw; means to which said screw is pivoted for jamming it on the beam independently of the movable jaw; and a spring in said bore tending to move said screw outwardly of said recess and thereby hold said jamming means in its jammed position. 80

5. A beam caliper, comprising a beam; a fixed jaw thereon; a second jaw movable along said beam and having a longitudinal recess, and also having a transverse slot and a bore communicating with said recess; a micrometer screw movable into said recess; an adjusting nut on the screw movable therewith into said slot to couple the screw to the movable jaw; a jamming member connected to said screw and adapted for engagement with the beam; a braking member within the movable jaw to which the screw and its jamming member are pivoted, said braking member being cooperative with said jamming member; and a spring in said bore tending to move said screw outwardly of said recess and thereby hold said jamming member in its jammed position. 90

6. A beam caliper, comprising a beam having a longitudinal groove; a fixed jaw thereon; a second jaw movable along said beam and formed with a longitudinal recess at one side thereof, and with a transverse slot intersecting said recess; a micrometer screw movable into said recess; an adjusting nut on said screw movable therewith into said slot to couple the screw to the movable jaw; a jamming head on the inner end of the screw for engagement with the beam; and a two-armed braking member loosely fitting in a second recess in the movable jaw and having one arm slidably engaged in the beam groove and the other arm pivotally connected to said jamming head. 100

7. A beam caliper, comprising a beam having a longitudinal groove; a fixed jaw thereon; a second jaw movable along said beam and formed with a longitudinal recess at one side thereof, and with a transverse slot communicating with said recess; 115

a micrometer screw movable into said recess; an adjusting nut on said screw movable therewith into said slot to couple the screw to the movable jaw; a jamming head 5 on the inner end of the screw for engagement with the beam; a two-armed braking member loosely fitting in a second recess in the movable jaw and having one arm slidably engaged in the beam groove and the 10 other arm pivotally connected to said jamming head; and a spring mounted in the bore of the movable jaw and tending to move said screw outwardly of the first-named recess and thereby hold the jamming 15 head in its jammed position.

8. A beam caliper, comprising a beam having a fixed jaw thereon; a movable jaw slideable on said beam and having a slot therein; a micrometer screw on said movable jaw; a nut threaded on said screw and 20 adapted to be swung into and out of said slot; and clamping means connected with said screw and adapted to be actuated by the same, whereby the screw is clamped to or released from said beam according as said 25 nut is swung into or out of engagement in the slot.

In testimony whereof I affix my signature.

KARL KISSENDORFER.
